UNITED STATES PATENT OFFICE.

ROBERT B. SUMMERS, OF OKMULGEE, OKLAHOMA.

DITCHING-MACHINE.

1,272,144.

Specification of Letters Patent.

Patented July 9, 1918.

Application filed October 12, 1917. Serial No. 196,244.

To all whom it may concern:

Be it known that I, ROBERT B. SUMMERS, a citizen of the United States, residing at Okmulgee, in the county of Okmulgee and State of Oklahoma, have invented new and useful Improvements in Ditching-Machines, of which the following is a specification.

This invention relates to ditching machines and has for one of its objects, the provision of a machine of this nature of extremely simple and practical construction, which is devoid of cumbersome and intricate working parts and which has a multiplicity of adjustments.

Another object of the invention is to provide in a ditching machine, a plow mounted in advance of an inclined elevator and being vertically adjustable with the elevator.

A further object of the invention consists in the provision of a ditching machine, which by simple and easily operable means may be leveled irrespective of the inclination of the ground over which it is working.

A further object of the invention is to provide a machine especially useful in pipe lining, trenching, and the like, and having means for discharging the excavated material adjacent to the side of the ditch.

The invention also aims to generally improve ditching machines to render them more practical, useful and commercially desirable.

With these and other objects in view, as will become more apparent as the description proceeds, the invention consists in certain novel features of construction, combination and arrangement of parts as will be herein-after fully described, illustrated and claimed.

In the drawings,

Figure 1 is a side elevation of a ditching machine constructed in accordance with my invention.

Fig. 2 is a top plan view of the machine.

Fig. 3 is a side elevation of the front half of the machine, showing the plow and conveyor in partly elevated position.

Referring in detail to the drawings by numerals, 1 designates as an entirety the frame of the ditching machine, said frame having parallel side bars 2. A bolster 3 extends transversely under the frame in engagement therewith adjacent its forward end and carries on each of its terminals a housing 4 to accommodate respectively the wheel standards 5. These standards are

vertically slidable through the housings or guides 4 and are swiveled at their lower ends to caster arms 6 on the lower portions of which are journaled the front wheels 7 as shown.

A bolster 8 extends transversely under the frame 1 adjacent its rear end and carries housings or guide sleeves 9 which extend respectively from the rear wheel standards 10 to the lower ends of which are connected the 65 wheels 11.

Each side bar 2 of the frame carries a forward raising and lowering lever 12 pivotally supported intermediate its ends by the bracket 13 on a horizontal pivot. Each lever 70 extends longitudinally of the frame and is pivotally connected at its forward end as at 14, to the upper terminal of the corresponding standard 5.

A second pair of raising and lowering or 75 leveling levers 15 are pivoted to the sides 2 intermediate their ends on horizontal pivots supported by brackets 16. These levers extend longitudinally of the frame and are pivotally connected at their rear ends to the 80 upper terminals of the standards 10 as indicated at 17. The inner ends of the two levers on each side of the frame terminate in spaced relation to one another and are connected by a chain or other flexible connection 18 which latter is connected centrally of its ends to a chain 19. The chains 19 are trained over pulleys 20 carried by brackets 21 and are wound in opposite directions about a drum 22 and fixed thereon. This 90 drum extends longitudinally of the frame and is fixed on a shaft 23 extending upwardly to a turning arm or lever 24. The lever may be swung from side to side to rotate the drum and may be locked in any set 95 position by means of the latch mechanism as shown. The rotation of the drum winds thereon one of the chains 19 and unwinds therefrom the other chain so it will be seen that since these chains operate upon the 100 levers 12 and 15, that the machine may be quickly leveled.

The earth is excavated by a plow share 25 having vertical side wings 26 which taper upwardly as shown. Each wing is slidably 105 and adjustably connected to a plow beam 27 by means of a clamp 28 having a sliding engagement with the beam and adapted to be locked thereto as shown. Pivots 29 connect the lower rear corners of the plow share re- 110

spectively, to the rear terminals of the plow beams as shown. These beams are somewhat J shaped and are respectively connected at their forward ends by chains 30 to tilting levers 31. Each lever is pivoted intermediate its ends to a bracket arm 32. The tilting levers extend between the side bars 2 of the frame and are each connected by a rod 33 to an operating lever 34 pivoted 10 as at 35 and capable of being locked to the segmental rack 36 in any adjusted position by the latch 37.

Each plow beam is pivotally connected intermediate the ends of its long arm 38 as at 15 38' to the lower end of a rack bar 39 which extends vertically through a bracket 40 supported on the frame 1. The rack bar meshes with a binding or gear 41 which is connected to a hand wheel 42 and rotatable therewith. 20 By turning the hand wheel, the rack bars may be reciprocated vertically to raise and lower the plow share and by operating the lever 34 the tilting levers 31 may be moved to rotate the plow beams upon the lower ends 25 of the rack bars. The operator's seat 43 is mounted convenient to the operating levers and to the handwheels. The plow share is connected in advance of an inclined elevator 44 to discharge the excavated earth on to the 30 traveling elevator or conveyer belt 45. The elevator includes a pair of side members 46 which are connected respectively to the plow beams 27 and which are pivotally supported at their upper ends on a transverse pivot rod 35 47. 48 designates horizontal side members fixed between the frame bars 2 to coöperate with the side members 46 of the elevator. The conveyer belt 45 is continuous and runs over roller tracks formed by rollers 49. These 40 rollers are relatively short and do not extend very far from the side members to which they are journaled. A pair of continuous sprocket chains 50 are secured to the opposed or inner sides of the belt adjacent their edges 45 to reinforce the belt and to drive the same. These sprocket chains contact the rollers 49, and are driven by sprocket wheels 51 fixed to a shaft 52 to which is secured a driving gear 53 driven from a driving sprocket 54 by a 50 chain 55. The driving sprocket 54 is driven by the engine 56 through conventional means. Side boards 57 prevent the excavated ma-

terial from falling from the sides of the elevator.

The elevator discharges into a pan or receptacle 58 at the rear of the machine and in this receptacle is mounted a transverse conveyer 59 driven by suitable means 60 operated by the engine 56. The dirt may be discharged from either end of the pan 58 and 60 falls adjacent the side of the ditch so that it may be easily used for filling purposes when so desired.

As the machine is pulled along, the revolving cutters 61, secured to the beam 27, will 65 sharply define the sides of the trench or ditch and the plow share will excavate the earth in line with the cutters. The engine 56 drives the conveyer belt so that as the dirt is fed thereonto, it will be elevated and 70 discharged into the pan or box 58. The depth of cut may be adjusted by operating the elevating rack bars 39, or the tilting levers 75 12 and 15 by means of the controlled lever 24 as previously described.

From the foregoing description taken in connection with the accompanying drawings, it will be seen that I have provided a simple 80 and practical ditching machine having a multiplicity of adjustments which serve to render the machine highly desirable for the work intended.

What I claim is:

A ditching machine comprising a frame, a conveyer frame pivoted at its upper end to said frame, a pair of plow beams of J-shape connected to the lower end of said conveyer frame, a vertically extending rack bar having its lower end pivotally connected to the plow beams intermediate their ends, means on the frame for raising and lowering said rack bar, means connected with the front end of said beams for tilting the same on the rack bar and a plow share pivotally connected to the lower ends of the plow beams, upwardly extending side wings on said share, and means for adjustably connecting the upper ends of said side wings to the plow beams.

In testimony whereof I affix my signature.

ROBERT B. SUMMERS.
